UNITED STATES PATENT OFFICE.

WILLIAM W. COBLENTZ, OF WASHINGTON, DISTRICT OF COLUMBIA.

THERMOPILE.

1,081,365.

Specification of Letters Patent. Patented Dec. 16, 1913.

Application filed October 28, 1913. Serial No. 797,912.

(DEDICATED TO THE PUBLIC.)

To all whom it may concern:

Be it known that I, WILLIAM W. COBLENTZ, a citizen of the United States, and residing at Washington, in the District of Columbia, have invented certain new and useful Improvements in Thermopiles, of which the following is a specification.

This application is made under the act of March 3, 1883, chapter 143, (U. S. Statute 10 XXII, page 625), and the invention herein described and claimed may be used by the Government of the United States or any of its officers or employees in the prosecution of work for the United States or by any person 15 in the United States without the payment of any royalty thereon.

My invention relates to thermopiles and has for its object the generation of electricity directly from heat.

20 A further object of my invention is to provide an instrument of this nature, which, though compact in form and rigid in construction, will be so sensitive to heat that it may be used to advantage in the most refined physical experiments.

It is well known that if two dissimilar metals are joined together and heated at the junction that a small electric current will tend to flow. This tendency is greater or 30 less, depending upon the temperature at the juncture. For example, if a bismuth wire be connected at each of its ends to a silver wire and one junction is heated above the other there will be a tendency for current 35 to flow. If a closed circuit be provided there will be a continuous flow of current as long as such difference of temperature is maintained. Use is made of this well-known principle in this device, the parts being so 40 arranged that the heat rays are utilized to a very considerable extent, producing the result that very small differences of temperature may be distinguished if a sensitive galvanometer be used with this instrument.

45 One application to which I have put this device is the comparing and measuring the temperatures of various parts of the spectrum.

Other objects will be apparent in the detailed description which follows and from the drawings, in which—

Figure 1 represents diagrammatically the principle of the device. Fig. 2 represents one embodiment as it appears in practice.

50 Fig. 3 is a view similar to Fig. 2, but with

part of the box portion cut away to show the arrangement of the thermoelectric elements. Fig. 3a shows a modification. Fig. 4 is a view partly in elevation and partly in section along the line 4—4 of Fig. 2. Fig. 5 shows a front elevation of another embodiment of my invention. Fig. 6 represents a vertical section of Fig. 5. Fig. 7 is a perspective view of a holder with receivers thereon, as used in my device. Fig. 8 shows a plurality of said holders and indicates how the receivers of adjacent holders are overlapped. Fig. 9 is a diagram showing one of the ways the thermoelectric elements may be connected in circuit.

Similar reference characters refer to similar parts in all the figures.

Referring first to the diagrammatic showing of Fig. 1, 1 and 2 represent the thermal elements, which may be any of the substances common in thermal batteries, such as silver and bismuth. The wires 1 may be silver, while the wires 2 may be bismuth. These wires are connected, as shown, by means of soldering. The silver and the bismuth wires are secured to pieces of good heat conducting material 3, 4, such as tin, permanent unions being made by means of solder. These pieces of good heat conducting material 3, 4 are termed receivers for the purpose of this description. The receivers 3 are arranged adjacent one another and are meant to be heated, while the receivers 4 are meant to be shielded from the heat, thereby constituting the so-called cold junctions.

Referring to Figs. 2, 3 and 4, which illustrate one practical embodiment of my invention, a casing is shown, made up of a box portion 5 and a cover 6. Mounted within the box portion 5 is the holder 7, consisting of some suitable insulating material, such as porcelain or hard rubber. Mounted on this holder 7 are the wires 1 and 2, united by means of the solder to the receivers 3, 4. The string of wires and receivers may be mounted by means of pins 8. The particular means of mounting is unimportant, but the receivers 3 should be arranged in alignment and should overlap, as illustrated. The receivers should be backed with a coating of shellac or other suitable insulating material in order to prevent a short circuit between the thermal elements. Arranged over a suitable opening in the box portion 5

are the slides 9, which slides provide the aperture 9^a. The receivers 3, arranged in alinement as described above, are mounted in a position to be exposed to light or heat rays through the aperture 9^a. The receivers 3 are made sufficiently wide and are arranged in a strip sufficiently long to intercept all the light or heat rays entering the aperture 9^a. The overlapping arrangement assures a perfectly opaque curtain. The receivers are preferably blackened to assist in the absorption of radiant energy. It is also important when this device is to be used in refined physical experiments that the receivers on the hot and cold junctures should be symmetrical in area and emissivity, in order that the two sets of junctures may quickly assume the temperature of the surrounding atmosphere when the recesses 3 are not exposed to radiation through the aperture 9^a.

In Fig. 3^a is illustrated an alternative arrangement of the wires and the receivers. In this arrangement each of the wires 1, 2, of Fig. 3, is replaced by two wires, 1, 1 and 2, 2, in parallel. These wires may be mounted on pins 8 and joined so as to produce a series-parallel circuit as illustrated. The hot receivers are arranged to overlap as in Fig. 3. The advantages gained by this arrangement are an increase of rigidity due to the fact that the receivers are supported at their two ends. The series-parallel arrangement of the circuit reduces the internal resistance by approximately one fourth without decreasing the sensitivity. The symmetry of the hot and the cold junctions is maintained as in the preceding arrangement. By this construction the use of shell-lac or other insulating material may be avoided, thus decreasing the heat capacity and emissivity and hence increasing the radiation sensitivity. The necessary insulative between the successive hot receivers is obtained by slightly displacing them normal to the plane of the curtain. The inside of the casing should preferably be blackened to reduce to a minimum the amount of reflected light. The receivers 4, being shielded from the light and heat rays, are maintained at a lower temperature than the receivers 3, the consequence being a resultant difference in electromotive force at the ends of the string of elements. These ends are connected with the terminal binding posts 10, 10. The device may be mounted on any suitable base 11.

One application of the device just described is the comparison of the different parts of the spectrum. The arrangement described with the long narrow aperture illustrated makes comparisons of the different parts of the spectrum very easy, the aperture admitting light from that portion only of the spectrum which it is desired to

examine. When the device is being used for this purpose the terminal binding posts 10 will be connected with a sensitive galvanometer.

In Figs. 5 to 9 is illustrated another embodiment of my invention. A casing is provided by the box 15 and the cover plates 16 and 17, the plate 16 being provided with a suitable opening to permit the entrance of the light and heat rays. The casing may be suitably mounted upon a base 11. Said casing may be rectangular in section, as illustrated, or may be of any other contour desired. Suitably mounted within the box 15 are lugs 18, which, with the cross bars 19 and suitable bolts, form the supporting means for the holders 20. These holders, which may be of ivory, hard rubber, or any other suitable insulating material, support the elements 1, 2 and the receivers 3, 4. The elements 1, 2 are united in strings, as in the embodiment of my invention described above, and are mounted on three sides of the holders 20, as best illustrated in Fig. 7, being held in place by means of the pegs 90 21. As illustrated in Fig. 7, the receivers 3 on each holder are overlapped, and as illustrated in Fig. 8, the receivers 3 of the various holders are overlapped. This arrangement provides an opaque curtain of receivers for the hot junctures. As in the embodiment of my invention described above, the receivers should be backed with a coating of some insulating material, such as shellac, to prevent short circuiting. In this embodiment also the receivers are preferably blackened to assist in the absorption of radiant energy. Also, the inside of the casing should be blackened to reduce to a minimum the reflection of light. With certain applications of this device it is important that the receivers on the hot and cold junctures be symmetrical in area and emissivity, though of course it is to be understood that the receivers 4 may be omitted 110 if desired.

A high radiation sensitivity may be attained by choosing the diameters of the two wires forming the thermal elements, so that the ratio between the heat conductivity 115 and the electrical resistance is the same in both.

In Fig. 9 I show a simple diagram illustrating one way in which the elements on the various holders may be connected in circuit, in this case the elements of two holders being connected in parallel by means of the wires 23 to the galvanometer 22. It will be evident that the elements may be connected in a variety of ways to any translating device desired.

Having thus described my invention, what I claim as new and desire to secure by Letters Patent is:

1. In a thermal generator, a shield pro- 130

vided with an aperture, a series of thermal elements supported behind said shield, said thermal elements being joined to form hot junctures and cold junctures, receivers of heat conducting material joined to said elements at the hot junctures, said receivers being overlapped to form an opaque curtain arranged behind said aperture.

2. In a thermal generator, a plurality of 10 receivers, wires of dissimilar metals joined to said receivers, a plurality of ends of similar wires being joined near the ends of each receiver and supporting means for said wires.

15 3. In combination, a plurality of adjacent holders, a plurality of thermal elements, arranged on three sides of each of said holders, said elements being joined to form hot junctures and cold junctures, heat conducting 20 receivers joined to said elements at the hot junctures, the receivers on each holder overlapping one another to form a curtain on each holder and the curtains on adjacent holders overlapping each other.

4. In combination, a plurality of adjacent 25 holders, a plurality of thermal elements, arranged on three sides of each of said holders, said elements being joined to form hot junctures and cold junctures, said hot junctures being arranged on sides of said holders between the sides on which the said cold junctures are arranged, heat conducting receivers joined to said elements at said hot junctures, the receivers on each holder overlapping one another to form a curtain on 30 each holder and the curtains on adjacent holders overlapping each other to shield the cold junctures from radiation.

5. A plurality of joined thermal elements, receivers attached to said thermal elements 40 at certain of the junctures, some of the said receivers overlapping.

In testimony whereof I affix my signature in the presence of two witnesses.

WM. W. COBLENTZ.
